UNITED STATES PATENT OFFICE.

WILLIAM H. RAMSEY, OF MINNEAPOLIS, MINNESOTA.

CURTAIN-STICK MACHINE.

1,079,992.

Specification of Letters Patent.

Patented Dec. 2, 1913.

Application filed March 6, 1913. Serial No. 752,521.

To all whom it may concern:

Be it known that I, WILLIAM H. RAMSEY, a citizen of the United States, residing at Minneapolis, in the county of Hennepin and 5 State of Minnesota, have invented a new and useful Curtain-Stick Machine, of which the following is a specification.

The present invention relates to improvements in curtain stick machines, this particular machine being an improvement upon the 10 U. S. Letters Patent No. 549,747, dated November 12, 1895, the improvement residing in the simplification of the machine therein shown, whereby the curtain stick is more 15 quickly and firmly secured in the ends of the curtain or shade, due to the elimination of the objectionable features of said patented structure and the addition of means whereby the vertically movable and swing- 20 ing member or blade is readily operated from the front of the machine to maintain the sticks of the curtain in the relative position during the fastening of the end of the curtain thereto.

25 A further object of the present invention is the provision of a curtain stick attaching machine having an inclinedly movable folding blade, a horizontally movable finishing blade, and a vertically disposed transversely 30 swingable and movable presser blade or bar, which is limited in its transverse movement and retained at all times relatively to the machine.

35 A still further object of the invention is the provision of a base having stationary means carried thereby to coact with three blades to receive the sticks and assist in folding the curtain or shade about the said stick to produce a secure fastening of the stick to 40 the curtain or shade.

With the foregoing and other objects in view which will appear as the description proceeds, the invention resides in the combination and arrangement of parts and in 45 the details of construction hereinafter described and claimed, it being understood that changes in the precise embodiment of the invention herein disclosed can be made within the scope of what is claimed without departing from the spirit of the invention.

In the drawings—Figure 1 is a top plan view of the complete machine. Fig. 2 is a side elevation thereof. Fig. 3 is a section taken on line 3—3 of Fig. 1. Figs. 4, 5 and 55 6 are detail views showing the three main steps necessary in attaching the sticks to the

curtain or shade material. Fig. 7 is a detail cross section through the lower end of a curtain or shade with the stick attached thereto by the present machine.

Referring to the drawings, the numeral 1 designates the base of the machine, which has uprising therefrom at two ends thereof, the two inverted U-shaped metal uprights 2, whose upper portions are secured to the under side of the transverse bars 3—3', and provide the two slots 4—4' adjacent the rear under surface thereof, said slots being lined with metal to prevent undue wear at this point, and being sealed by the connecting portion of the respective uprights. Disposed for sliding and swinging movement within the respective slots, are the headed pins *a* which are connected to form the axis for the cross-head 5, said cross head 5 being bodily movable transversely and for vertical swinging movement relatively to the bars 3 and 3' and the upper surface of the base 1.

Connected to the respective ends upon the upper surface of the cross-head 5, are the two bracing arms 6, each one of which is disposed to seat within the guiding plates 7, one connected to each inner face of the bars 3—3', while in order to limit the vertical movement of the cross-head 5, the pins 8 are employed and are connected to the inner faces of the respective bars 3 and 3', and in the path to engage the bracing arms 6 when the cross-head 5 is moved to its further rearward movement and tilted so that the various parts carried thereby permit of free access to the base of the machine between the bars 3—3'.

Connected to the under side of the cross-head 5 intermediate of its ends and projecting forwardly thereof, are a plurality of L-shaped arms 9, braced by the plate 10, the short outer terminals of which have connected thereto, the presser blade 11, the purpose of which will presently appear.

In order to manipulate the cross-head and the presser blade relatively to the base of the machine, a handle 12 is connected to the upper face of the cross head 5 and projects forwardly and in parallel with the center L-shaped arm, the same being braced thereto, by means of the bracing plate 13, the vertical post 14 and the upper bracing plate 15, said bracing plate 15 being connected to such handle and to the cross-head 5, as clearly illustrated. By this means, the

presser blade may be moved transversely between the bars 3—3', and may be tilted rearwardly and above said bars to permit of the introduction and removal of the sticks 5 and shade before and after the fastening of the sticks thereto. It will be noted that the gripping portion of the handle is disposed forwardly of the base, and is therefore in ready access for movement of the blade 11 transversely of the base or vertically away therefrom, thus placing the same at the ready disposal of the operator, and in a more convenient position than in the structure above referred to.

15 Secured to and parallel with the front portion of the base of the machine, is a bed 18, provided with the longitudinally disposed limiting shoulder 19, the inclined folding blade guiding plane 20, the shoulder 20 21, the longitudinal recess 22 and the lip or longitudinally projecting strip 23, this portion providing with the longitudinally disposed strip 25, the recess or space 26 longitudinally of the machine.

25 Secured to the inclined portion 20 of the bed 18 by means of a pin and slot 27—28, is a longitudinally and inwardly movable folding blade 29, while secured by the pin and slot connection 30—31 to the strips 25 30 upon the base is the oppositely moving finishing blade 32. These blades have the same movement and operation, as the blades shown in the patent heretofore mentioned, and are provided respectively with the operating handles 34 and 35, which are pivoted at 33 to the base of the machine. The lever 34 is provided with an operating handle 36, while the lever 35 is provided with an operating handle 37, said levers being connected to their respective blades through the medium of the links 38 and 39, respectively, as clearly illustrated in Fig. 1.

The operation of the blades 11, 29 and 32, are identical with the blades illustrated in 45 the patent before mentioned, but the construction of the curtain stick device, as clearly shown in Fig. 7, is different and dispenses with the use of a cord therein. In this case, the sticks 40 and 40' are provided 50 with the flush or parallel opposed faces 41, the lower rounded edges 42 thereof, forming when the two sticks are assembled, and with the outer wall thereof, a substantially elliptical form. It will thus be seen, that with 55 the present machine, the construction and operation of the device as compared with that shown in the before mentioned patent, is greatly simplified, and by positioning the handle for operating the presser blade 11, 60 all handles of the device are readily accessible for manipulation to perform the various steps as illustrated in Figs. 4, 5 and 6 to produce the finished article as shown in Fig. 7. It is also apparent that by permitting 65 the cross-head 5 with the presser blade 11 to

be tilted rearwardly, that the presser blade will be moved above the base of the machine and in a plane substantially at right angles to the plane of the base, so as to permit of the ready insertion of the sticks 40—40' in 70 the respective grooves upon the base and their removal of the finished article from the machine. In order, however, to set forth the operation of the present machine, the detail fastening of the sticks 40—40' within 75 the end of the curtain shade material is as follows: The fabric composing the shade is led in from the rear under the presser bar 11 and drawn upon the folding plate to the back of the raised bed, where it is held in 80 place by one hand while the first part of the stick 40, is placed with its rounding face bearing the shade downward upon the recess and its beveled edge uppermost and remote from the operator. The presser bar 11 is 85 then turned upon the stick to hold it in position. The lever is then moved to the left, whereby the folding blade 29 through its actuating pin and slot connection 27—28 is caused to slide down and rearward. This 90 completes the first fold. The presser bar 11 is then turned up and back to assume the dotted line position in Fig. 3, and the thin steel clencher plate *c* is now laid upon the fabric and over the groove formed by the 95 first raised bed or projection and the cleat and upon this clencher is placed the second part 40' of the stick with its bevel uppermost and toward the operator. These two sticks are now pressed downward which 100 bears them and the fabric beneath them down into the groove of the base. The operator now turns the presser bar 11 upon the stick and the clencher plate by means of the lever, presses down and holds the same in 105 position. The second lever operating the second folding blade 32 is moved to the left, bringing the fabric into position over the second stick 40'. The presser bar 11 is then turned up and back to assume the dotted line 110 position. The first lever operating the first folding blade 29 is then moved to the right releasing the first fold with the first part of the stick 40. The part 40 of the stick with the surrounding shade is then pressed down 115 with the hands until the same begins to bind on the second plate or stick 40'. The same is then held in this position and the second lever is moved to the right thus releasing the second blade 32. The parts are now completely compressed either by the fingers or 120 by the movement of the blade 11 upon the parts, and the nail or staple *C* is driven after being placed in the position, as shown in Fig. 6. The staple or nail is clenched by 125 means of the clenching plate, and the curtain is now drawn to and through the rear of the machine and the clencher plate *c* is removed.

What is claimed is:

1. A machine of this character, including 130

a base, a frame carried thereby, a folding and a finishing blade mounted for movement to and from each other upon the base, and a presser blade mounted in the frame 5 for transverse sliding movement and for vertical swinging movement relatively to the base.

2. A machine of this character, including a base, a frame carried thereby, a folding 10 and a finishing blade mounted for movement to and from each other upon the base, and a presser blade mounted in the frame for transverse sliding movement and for vertical swinging movement relatively to the base, said base being provided with parallel stick and shade receiving means one to each of the first two blades, whereby the presser blade may be disposed above either one at a time to assist in holding the shade 15 and stick in position.

3. A machine of this character, including a base, said base being provided with two parallel recesses longitudinally thereof, a frame carried transversely of the base, a folding blade for movement to and from one of the recessed portions, a finishing blade 25 movable to and from the other remaining recessed portion of the base, and a presser blade mounted in the frame for transverse movement relatively to the recessed portions 30 of the base, and for vertical swinging movement to and from the base.

4. A machine of this character, including a base, said base being provided with two parallel recesses longitudinally thereof, a frame carried transversely of the base, a folding blade for movement to and from one of the recessed portions, a finishing blade 35 movable to and from the other remaining recessed portion of the base, a presser blade mounted in the frame for transverse movement relatively to the recessed portions of the base, and for vertical swinging movement to and from the base, 40 and cooperating means carried by the presser blade and the frame for limiting the vertical movement of the blade away from the base.

5. A machine of this character, including a base, a frame carried thereby, a folding 50 blade and a finishing blade mounted for movement toward each other, a bar mounted for transverse and vertical swinging movement in the frame above the base, a handle projecting outwardly therefrom and normally substantially at right angles to the base, and a presser blade carried by said bar and disposed downwardly at right angles thereto for coercive action with the folding and finishing blades.

6. A machine of this character, including

a base, two bars mounted above the base and transversely thereof, said bars being disposed in parallel, two longitudinally disposed blades mounted upon the base, said blades being disposed to move transversely 65 of the base, two handles, one to each blade for operating the blades, a cross head disposed between the bars and capable of a limited transverse movement above the base and a swinging movement to and from the 70 base, a presser blade connected to and carried by the cross head, said presser blade being disposed at right angles and below the cross head for engagement with the base, and a handle disposed to project normally 75 at right angles to the base connected to the cross head for manipulating the cross head and presser blade.

7. A machine of this character, including a base, two bars mounted above the base and transversely thereof, said bars being disposed in parallel, two longitudinally disposed blades mounted upon the base, said blades being disposed to move transversely 80 of the base, two handles, one to each blade 85 for operating the blade, a cross head disposed between the bars and capable of a limited movement above the base and a swinging movement to and from the base, a presser blade connected to and carried by 90 the cross head, said presser blade being disposed at right angles to and below the cross head for engagement with the base, a handle disposed to project normally at right angles to the base connected to the cross head for 95 manipulating the cross head and presser blade, and means connected to the bar and disposed in the path of the cross head for limiting the movement of the cross head away from the base.

8. In a machine of this character, the combination with a base, a frame carried thereby, a folding blade and a finishing blade mounted upon the base for movement toward and away from each other, a cross 105 head, headed pins carried thereby and forming an axis for the cross head, said headed pins being journaled in the frame for transverse sliding movement and swinging movement to and from the base, a handle for operating the cross head, and a presser blade carried by the cross head for coaction with the folding and finishing blades.

In testimony that I claim the foregoing as my own, I have hereto affixed my signature in the presence of two witnesses.

WILLIAM H. RAMSEY.
